Edward Tyrrell Inventor
By his Attorney *Wood & Bond*

UNITED STATES PATENT OFFICE.

EDWARD TYRRELL, OF BROOKLYN, NEW YORK.

FOUNTAIN-PEN.

SPECIFICATION forming part of Letters Patent No. 443,017, dated December 16, 1890.

Application filed July 24, 1890. Serial No. 359,784. (No model.)

To all whom it may concern:

Be it known that I, EDWARD TYRRELL, a citizen of the United States, and a resident of Brooklyn, in the county of Kings and State 5 of New York, have invented certain new and useful Improvements in Fountain-Pens, of which the following is a specification.

My invention relates to the construction of feed-tubes for fountain-pens.

10 The object of my invention is first to provide an air-vent in the feed-tube above the delivery-orifice, thereby securing a most steady flow of ink.

Another object of my invention is to provide 15 an adjustable feed-tube that can be moved longitudinally and angularly in the barrel of the pen and accommodate itself to different classes of pens.

Another object of my invention is to provide 20 a leader, so as to secure a positive flow of the ink.

The various features of my invention will be fully set forth in the description of the accompanying drawings, making a part of this 25 specification, in which—

Figure 1 is a central vertical longitudinal section of my improvement in position for use. Fig. 2 is a top plan view of the feed-tube. Fig. 3 is a section on line $x-x$, Fig. 2.

30 Fig. 4 is a modification of Fig. 2. Fig. 5 is a section on line $v-v$, Fig. 4.

1 represents the barrel of the pen, and 2 the ink-reservoir, which is of ordinary construction.

35 3 shows the pen-holder inserted in the barrel of the pen.

Fig. 2 shows the preferred form of feed-tube, which is provided with a conical or ball-shaped boss 4. 5 represents the feed-orifice 40 which conveys ink to the pen 6. 7 represents an air-vent placed above the feed-orifice 5. 8 represents an ink leader or conductor. This leader is preferably made of sufficient vertical depth to fill the tube of the feed and narrower in cross-section, as shown in Fig. 3, so that the ink will freely flow on both sides of said leader, which is tapered down and projects forward, resting on the base of the tube below the feed-orifice, which is sufficiently

small to allow the ink to flow around it out 50 of the feed-orifice 5. By reason of having the conical or ball-shaped boss 4 this feed-tube can be adjusted longitudinally to various angles or positions, as shown in Fig. 1, to feed any style or length of pen. It bears 55 lightly against the pen, and the softest pen may be employed and a uniform flow of ink supplied. By means of the vent 7 this uniform flow is more easily obtained, as the entrance of the air through the feed-orifice is 60 avoided. The leader 8 projects up into the ink in the barrel 2 and serves to conduct it freely down and prevents the liability of the pen clogging up and secures a uniform flow. This leader, however, may be omitted and 65 still good results be obtained, owing to the air-vent 7.

In Fig. 4 I have shown another modification, in which the feed-tube is adjustable longitudinally only, and used when one particular style of pen of different lengths is desired to be employed, as the air-vent 7 will secure a comparative uniform flow or supply 70 of the ink to the pen even without the use of the leader. Still a leader improves it when 75 the ink is thick.

Having described my invention, what I claim is—

1. A feed-tube for a fountain-pen, provided with the conical boss 4, for adjustably connecting the same to the barrel of the pen, substantially as specified.

2. A feed-tube for a fountain-pen, having the conical boss 4 and the air-vent 7, pierced in the tube above the delivery-orifice 5, substantially as specified.

3. A feed-tube for a fountain-pen, provided with the conical boss 4 and the leader 8, projecting up into the barrel of the pen and terminating under the orifice 5, substantially as 90 specified.

In testimony whereof I have hereunto set my hand.

EDWARD TYRRELL.
